UNITED STATES PATENT OFFICE.

HOWARD S. FRECH, OF BROOKLYN, NEW YORK.

INTERNAL-COMBUSTION ENGINE.

1,229,438.

Specification of Letters Patent. Patented June 12, 1917.

Application filed August 31, 1912. Serial No. 718,085.

To all whom it may concern:

Be it known that I, HOWARD S. FRECH, a citizen of the United States, residing at Brooklyn, in the county of Kings and State 5 of New York, have invented new and useful Improvements in Internal-Combustion Engines, of which the following is a specification.

My invention relates to internal combustion engines.

One object of my invention is to provide a single valve serving as an inlet and as an exhaust valve.

Further objects of my invention are to 15 eliminate the necessity of providing reciprocating parts for a valve of this type and to reduce the number of moving parts thereof.

A further object of my invention is to 20 provide a single valve fulfilling intake and exhaust functions, working in combination with the cylinder, having openings coöperating with the valves to effect the intake of the explosive mixture and exhaustion of the 25 spent gases.

Another object of my invention is to provide in combination with the valve and cylinder, air intake means so that fresh air may be taken into the cylinder to assist in 30 the scavenging of the spent gases therefrom.

Specifically, my invention consists of a rotatable valve mounted between a piston and a cylinder provided with inlets to register 35 with the inlets of the cylinder, and moved or actuated through the sliding movement of the piston.

Other objects and advantages will appear 40 from the following specification, reference being had to the accompanying drawings, in which:

Figure 1 is a vertical sectional view of the major portion of a cylinder and piston with my improvements embodied in connection therewith.

Fig. 2 is a similar view of the upper portion of the cylinder and showing the baffle.

Fig. 3 is a cross-section through the upper portion of the engine showing the single 50 port at the upper end of the sleeve valve as being located between the exhaust and intake ports of the cylinder.

Fig. 4 is a diagrammatic view illustrating a development of the valve cam grooves,

55 Fig. 5 is a detail diagrammatic section of the auxiliary exhaust opening of the valve.

in registration with the auxiliary exhaust port,

Fig. 6 is a cross section on the line 6—6 of Fig. 5, and 60

Fig. 7 is a cross section on the line 7—7 of Fig. 5.

By referring to the drawings, it will be observed that 1 designates an engine cylinder in which a piston 2 having a head 3 is movable. The piston 2 is reciprocated within the cylinder 1 by a connecting rod 4 which rotates upon the usual wrist-pin 5 of the piston 2. The other end of the connecting rod 4 is connected with the crank of the 70 crank shaft of the engine in the usual manner, the illustration of this connection being however omitted from the drawings.

A sleeve or valve 6 is mounted between the cylinder 1 and the piston 2 in such a 75 manner that the sleeve may rotate but not move vertically. The sleeve or valve 6 is provided with a single port near its upper end as indicated at 7 in Figs. 3 and 7. The port 7 is adapted to be moved into registration with an exhaust port 11 (see Fig. 3) in the cylinder wall 1, and an inlet port 8 also in the cylinder wall 1, upon rotation of the valve 6. The single port 7 thus performs the dual function of an inlet and exhaust port for the engine. When the port 7 is in registration with the exhaust port 11, it acts as the main exhaust port for the engine since when the port 7 is in such registration the greater volume of the products 85 of combustion are driven out of the port 11 through the action of the piston within the cylinder.

The valve 6 is also provided with a pair of nearly diametrically opposite ports 10 95 and 14 as shown in Fig. 6, the ports 10 and 14 being disposed some distance below the single port 7 as will be readily understood from Fig. 5. It may be stated that the distance between the port 7 and the ports 10 100 and 14, is approximately equal to the stroke of the piston.

The port 10 is an auxiliary exhaust port and is adapted to be moved into registration with the auxiliary exhaust opening 12 in 105 the wall of the cylinder 1. When the piston 2 moves to the position shown in Fig. 5 and having thus reached the end of the working stroke, the valve 6 will have accordingly rotated and brought the auxiliary 110 port 10 and auxiliary opening 12 into registration as shown so that a considerable

portion of the spent gases are permitted to rush out.

The port 14 which is nearly diametrically opposite the auxiliary exhaust port 10 will 5 almost immediately move into registration with an air inlet opening 14 in the cylinder wall 1. The piston 2 will of course have begun to ascend by the time the port 14 will have moved into registration with the opening 13, but the registering port 14 and 13 will present sufficient space to allow the 10 quantity of fresh air to flow into the cylinder. The fresh air in flowing into the cylinder through the registering ports will 15 strike the baffle 19 and be deflected toward the center of the cylinder.

It will be observed that the main port 7 is out of vertical alinement with the port 10, the relative locations of the various ports in 20 the valve 6 being clearly shown in Figs. 6 and 7. It will thus be obvious that when the auxiliary exhaust port 10 is in registration with the exhaust opening 12, the single port 7 will be just about ready to come into 25 registration with the main exhaust port 11 as clearly shown in Fig. 7. By the time that the piston 2 moves upwardly far enough to cover the ports 10 and 14 at the lower portion of the valve 6, the main exhaust port 33 7 will have moved into full registration with the port 11 and the remaining products of combustion within the cylinder will be expelled therethrough.

The valve 6 is rotatably mounted between 35 the cylinder 1 and the piston 2. A plurality of tortuous and intersecting grooves 15 and 15^a are formed on the inner surface of the valve 6. A development of these grooves is 40 illustrated in Fig. 4. It will be understood from Fig. 4 that the grooves 15 and 15^a are imagined to have been unwrapped from the inner surface of the valve 6 and spread out longitudinally, the lateral confines of the figure representing 360° or the circumference 45 of the inner surface of the valve 6.

The piston 2 is provided with heads or 50 rollers 17 which are movable in the grooves 15 and 15^a on the interior surface of the valve 6. The rollers 17 are disposed diametrically opposite each other as shown in Fig. 1 and are mounted upon studs 16 secured in place by the nuts 18. A baffle 19 is secured on the head 3 of the piston 2 and the baffle 17 is set at an angle with the 55 head 3 so that the incoming charge of fresh air above referred to, in striking the baffle may be properly deflected toward the center of the cylinder.

The operation of the device is as follows: 60 The engine in the present embodiment is of the four stroke cycle type. The valve 6 is rotated as the piston 2 reciprocates by reason of the engagement of the rollers 17 with the cam grooves 15 and 15^a.

65 Let it be assumed that the valve 6 has ro-

tated to such a position where the single port 7 has become located directly between the exhaust port 11 and the intake port 8 as shown in Fig. 3. The engine cylinder is supposed to be completely scavenged at this time and upon continued rotation of the valve 6 the port 7 will move into registration with the intake port 8. The piston 2 now moving upon its induction stroke draws in a charge of gas through the registering ports 7 and 8. The piston 2 after having reached the end of its induction stroke, will move upon its compression stroke whereupon the compressed gas within the cylinder is ignited. The piston 2 is thus moved upon its working stroke and when it reaches the position shown in Fig. 5, the valve 6 will have accordingly rotated so that the auxiliary exhaust ports 10 and 12 will have moved into registration thus permitting a 85 considerable portion of the spent gases to escape therethrough.

As the piston 2 now moves upwardly again and just before it leaves the zone occupied by the ports 13 and 14, the ports 13 and 14 will have come into registration and will have permitted a charge of fresh air to flow therethrough. The charge of 90 fresh air in striking the baffle 19 is deflected toward the center of the cylinder.

The piston 2 now moves upon its exhaust stroke, the single port 7 having in the meantime moved from the position shown in Fig. 7 until it registers completely with the exhaust port 11, when the residue of the burnt gases within the cylinder will be expelled through the main exhaust port 11. The foregoing is the action which takes place and relates directly to the coöperation of 100 the piston 2 with the valve 6 and the respective ports in the valve and in the cylinder wall 1.

The manner of operation for the rotation of the valve 6 by provision of the engagement of the roller 17 of the piston 2 therewith, is as follows: When the rollers 17 are located at the points *c* and *c'* in the respective cam grooves 15 and 15^a, then the piston 2 is at the limit of its inward stroke and is about to begin its induction stroke. The single port 7 in the valve 6 will then be disposed between the ports 11 and 8 as shown in Fig. 3.

As the piston 2 descends, the rollers 17 engage the cam grooves 15 and 15^a at the 115 curved portions *e* and *e'*. The valve 6 is thus driven in a counter-clockwise direction as indicated by the arrow in Fig. 3 until the points indicated *f* and *f'* are reached at 120 which time the single port 7 of the valve is in complete registration with the intake port 8 in the cylinder wall 1. As the piston 2 continues its induction stroke, the rollers 17 in engaging the curved portions *g* and *g'* of 125 the cam grooves 15 and 15^a, will continue the 130

rotation of the valve 6 until the piston 2 has reached the limit of its outward stroke and the rollers 17 have reached the points *h* and *h'*. When the points *h* and *h'* are reached, 5 the valve 6 will have been rotated such an extent that the single port 7 will have been moved completely out of registration with the inlet port 8. The cylinders now filled with fresh gas and the piston 2 is ready to 10 commence its compression stroke.

As the piston 2 now moves upon its inward or compression stroke, the rollers 17 will move over the points *i* and *i'* of the cam groove 15 and 15^a, and continue to drive the 15 valve 6 around in the direction in the arrow in Fig. 3 until the points *j* and *j'* are reached. When the points *j* and *j'* are reached the piston 2 will have reached the limit of its compression stroke and the compressed 20 charge again be ignited and the piston 2 accordingly again driven outwardly on its working stroke.

The rotation of the valve 6 now momentarily ceases while the piston 2 traverses the 25 distance between the points *j* and *j'*, and the points *k* and *k'* shown in Fig. 4. As soon as the points *k* and *k'* are passed by the piston 2 and consequently by the rollers 17, said rollers will engage the curved portions *l* and 30 *l'* of the grooves 15 and 15^a, when the valve 6 will again be rotated until the points *m* and *m'* are reached. When these points *m* and *m'* are reached the piston 2 will be located at the limit of its outward and working 35 stroke and will assume the position shown in Fig. 5. The auxiliary exhaust ports 10 and 12 will then be in registration and a part of the products of combustion will rush out as explained above.

40 The piston 2 will now move inwardly again upon its exhaust stroke but the valve 6 however remains stationary momentarily while the piston 2 moves through a distance represented between the points *n* and *n'* and 45 the points *m* and *m'*. As soon as the points *n* and *n'* are passed by the rollers 17, the curved portions *o* and *o'* will be engaged thereby whereupon the valve 6 will again be rotated. It will be understood that as the 50 piston 2 moves upon its inward or exhaust stroke from the points *m* and *n'*, that the single port 7 will have been moved into registration with the exhaust port 11 and the residue of the products of combustion 55 expelled. When the curved portions *c* and *c'* are reached, the valve 6 assumes the position indicated in Fig. 3, and when the points *h* and *h'* are reached, the single port 7 has passed the inlet port 8 in readiness for the 60 commencement of another cycle of the same operation above enumerated.

It is to be understood that I have de-

scribed the preferred embodiment of my invention herein, and that changes therein may be made within the spirit and scope of 65 the appended claims.

Having thus described my said invention, what I claim and desire to secure by Letters Patent is:—

1. An internal combustion engine including a cylinder having an auxiliary exhaust port and an air inlet port, said ports being in diametrical opposition, a sleeve valve rotatable inside of the cylinder, the sleeve valve having an auxiliary exhaust opening and an 70 air opening, said openings being out of diametrical opposition, the sleeve valve having a pair of grooves on the inside surface, a piston movable inside of the sleeve valve, and rollers on the piston movable in the respective grooves, whereby the sleeve valve is rotated to momentarily move the air opening into registration with the air port as the piston begins the exhaust stroke.

2. An internal combustion engine including a cylinder having a main exhaust port at its upper end, a sleeve valve rotatable inside of the cylinder the sleeve valve having a single opening registerable with the main exhaust port, the sleeve valve having grooves 80 on its inside surface, a piston reciprocable inside of the sleeve valve, and rollers on the piston movable in the grooves said grooves including diagonal and vertical sections whereby the speed of rotation of the sleeve 95 valve is accelerated as the single opening approaches the exhaust port and the piston performs its working stroke, and momentarily stopped as the single opening registers with the exhaust port and the piston performs a part of its exhaust stroke.

3. An internal combustion engine including a cylinder having inlet and exhaust ports at its upper end, and an auxiliary exhaust port and an air inlet port at its lower end, a 105 piston having a valve rotating roller, a sleeve valve disposed between the piston and the cylinder said valve having openings registerable with the respective cylinder ports, said valve having a groove for receiving the 110 roller, the groove including curved and diagonal stroke-sections varying in degrees of extension, and vertical stroke-sections having curved termini, the stroke-sections of the groove obtaining the rotation, acceleration 115 of rotation and stopping of the valve in succession as the various ports and openings are moved into registration and the piston performs its strokes.

HOWARD S. FRECH.
